US0D1043070S

(12) **United States Design Patent** (10) **Patent No.:** **US D1,043,070 S**
Holmes (45) **Date of Patent:** **** Sep. 24, 2024**

- (54) **SHOE**
(71) Applicant: **NIKE, Inc.**, Beaverton, OR (US)
(72) Inventor: **Edmund Holmes**, Portland, OR (US)
(73) Assignee: **NIKE, Inc.**, Beaverton, OR (US)
(**) Term: **15 Years**
(21) Appl. No.: **29/928,031**
(22) Filed: **Feb. 7, 2024**

Related U.S. Application Data

- (62) Division of application No. 29/775,646, filed on Mar. 24, 2021, now Pat. No. Des. 1,029,469.

(57) **CLAIM**

The ornamental design for a shoe, as shown and described.

DESCRIPTION

FIG. 1 is a bottom view of a shoe showing my new design; FIG. 2 is a bottom front perspective view thereof; and, FIG. 3 is a bottom rear perspective view thereof.

The claimed design includes only the solid lines. The remainder of the shoe, including the lighter grey photographic depiction and broken lines, forms no part of the claimed design.

1 Claim, 3 Drawing Sheets
